UNITED STATES PATENT OFFICE.

ALFRED KELLER, OF ST. CROIX, SWITZERLAND, ASSIGNOR TO LOUIS PHILIPPE MERMOD, GUSTAVE ALFRED MERMOD, AND LEON MARCEL MERMOD, COPARTNERS TRADING AS MERMOD FRÉRES, OF ST. CROIX, SWITZERLAND.

LIQUID-DISTRIBUTER.

No. 846,032.

Specification of Letters Patent.

Patented March 5, 1907.

Application filed April 11, 1906. Serial No. 311,119.

To all whom it may concern:

Be it known that I, ALFRED KELLER, a citizen of Germany, residing at St. Croix, canton of Vaud, Switzerland, have invented 5 certain new and useful Improvements in Liquid-Distributors, of which the following is a full, clear, and exact description.

My invention relates to improvements in liquid-distributors, particularly for liquid soap.

The object of the invention is to provide a simple and easily-operable mechanism for distributing limited quantities of liquids when desired.

5 The invention consists in improvements the principles of which are illustrated in the accompanying two sheets of drawings.

The invention consists principally in a mechanism for controlling the discharge of 10 liquid.

Figure 1 is a vertical sectional view of a distributor embodying the improvements of 15 my invention. Fig. 2 is a plan view of the plunger-cylinder. Fig. 3 is a plan view of the valve-support and outlet member. Fig. 4 is a plan view of the valve-spider. Fig. 5 is a plan view of the valve-plate. Fig. 6 is a 20 vertical section of a somewhat-modified construction embodying my invention, only a fragment of the liquid-receptacle being shown. Fig. 7 is a side elevation of the same 25 detached from the liquid-receptacle. Fig. 8 is a plan view of the plunger-cylinder. Fig. 9 is a horizontal sectional view taken just 30 above the outlet-valve.

1 indicates the body of the receptacle for 35 containing the principal volume of liquid. In the form shown this is a glass globe. The shape of the receptacle and the material of 40 which it is constructed is, however, immaterial. To the liquid-receptacle is attached the mechanism containing the inlet and outlet valves and supplying the measuring-chamber.

2 indicates the upper part of the case, 45 which is preferably secured to the liquid-receptacle by a screw-threaded portion.

3 indicates the cylinder, having the measuring-chamber 4, the inlets 5 5, and the outlet 6. This is screwed into the casing member 2 and provides means for attachment of 50 the lower member 7 of the casing. In the bottom of the casing is located the outlet-valve.

8 indicates a vertically-movable discharge-nozzle forced upward by the spring 9.

55

10 is the valve-plate, supported by the spider 11, which in turn rests in the member 8.

12 indicates the outlet. Any liquid which is in the chamber 3 or outlet 6 is held back by the pressure of the valve-plate 60 against the lower end of the cylinder 3, which is preferably reduced in diameter to make a tighter seat.

13 is a plunger operable in the cylinder 4, which passes through the cap 14 of the liquid-receptacle and has a head 15, so that it may be readily operated by the hand.

65 16 is a spring normally holding the plunger or piston in its elevated position. The liquid-receptacle may be readily filled by 70 pouring liquid into the upper end of the hollow plunger, which has an outlet 17 into the interior of the receptacle.

When it is desired to discharge liquid from 75 the receptacle, the plunger 13 is pressed down. As soon as its lower end passes the inlet-ports 5 the liquid in the chamber 4 is forced down. The pressure overcomes the pressure of the spring 9 and depresses the valve-plate 10 sufficient to unseat it. Continued 80 downward movement of the plunger forces the liquid through the outlet 6 around the spider 11 into the interior of the valve-support 8 and through the outlet 12. The downward movement of the plunger 13 controls 85 the amount of liquid discharged. A greater or less amount of liquid may be obtained by depressing the plunger to a greater or less extent. The amount discharged is limited, however, to the capacity of the 90 chamber 4.

On Sheet 2 is shown a somewhat modified construction. In this form the lower end 7' of the case is screwed on to the upper portion of the casing 2'. The plunger-cylinder 3' has 95 long passages 5' 5', leading beneath the lower end of the plunger 13', when it is in its normal position. The laterally-extending pivoted lever 15' is adapted to force the plunger down against the pressure of the spring 16'. In this particular form the liquid-chamber 4' is smaller than in the form illustrated in Fig. 1, and the outlet-passage 6' is formed in a separate tip member 18. In both cases, however, the valve member 8 is vertically 105 guided in the casing, and the parts so fitted

that liquid can escape only through the outlet 12 when the plunger is depressed. The valves are so constructed that they operate immediately and directly upon depression of the plunger, yet there is no danger of leakage or discharge of liquid, except upon the intention of the operator.

What I claim is—

1. In a liquid-distributer, a liquid-receptacle, a cylinder having a normally open inlet in communication with said receptacle, a normally closed outlet, a plunger in said cylinder arranged to cut off said inlet when advanced, a valve at the outlet, a yielding nozzle supporting said valve, a liquid-passage through said nozzle and beyond the valve, and means to yieldingly move said nozzle toward said cylinder-outlet to close said valve against the same.
2. In a device of the character described, a cylinder, a plunger therein, a normally open inlet therein, an outlet, a valve for normally closing the same, a spring-pressed yielding nozzle supporting said valve, a discharge-passage through said nozzle, and means of communication through said nozzle and around said valve and leading to said nozzle-outlet when said plunger is depressed.
3. In a liquid-distributer, a cylinder having

an inlet and an outlet, a vertically-movable valve for said outlet comprising a supporting member having an outlet, a spider in said support, and a valve-plate carried by said spider.

4. In a device of the character described, a cylinder having an inlet and an outlet passage therein, a movable valve for said outlet comprising a combined movable valve-supporting member and discharge-nozzle, means in said nozzle for carrying said valve and a passage through said nozzle and around the valve therein to afford communication with the outlet, a casing surrounding said nozzle except at the end and a spring in the casing to move the nozzle to close the valve.

5. In a device of the character described, a piston-cylinder an inlet, an outlet, a valve for said outlet, a combined yielding valve-support and discharge-nozzle and a communicating passage leading from the valve proper to said nozzle-outlet, a spring surrounding said nozzle for moving it in a direction to cause the valve to close the outlet in the piston-cylinder.

ALFRED KELLER.
